BEAM COMPASS

Hugo Virus, Villa Park, Ill., assignor to Keuffel & Esser Company, Hoboken, N. J., a corporation of New Jersey

Application February 6, 1947, Serial No. 726,822

1. Claim. (Cl. 33—159)

1

This invention relates to improvements in a beam compass.

The invention is concerned primarily with providing means for adjusting one of the posts of a beam compass accurately to a predetermined position from which it will not be disturbed when it is firmly clamped to the beam.

Beam compasses conveniently comprise a bar on which at least one post is movable. The other post may or may not be adjustable along the beam. In precision work with a beam compass it is necessary to adjust one post with respect to the other with a high degree of accuracy and various means have heretofore been provided to move the adjustable post along the bar. Devices of the prior art in many instances were capable of very minute adjustment but when the post was clamped to the bar the adjustment was frequently disturbed so that the original setting was lost. Other devices for accomplishing this purpose were oftentimes complicated and difficult to manufacture. This invention is shown as to its preferred embodiment in the accompanying drawings wherein;

Figure 1 is a view in elevation (with one part in section) showing the complete beam compass.

Figure 2 is a view in section of a portion of the adjustable post and the adjusting mechanism; and,

Figure 3 is a view in section along the lines 3—3 of Figure 2.

Referring to the drawings and particularly Figure 1, the beam compass includes a bar or beam 2 which may be circular but is preferably irregular in cross section as by flattening a portion of the top (note Figure 3) in order that the two posts may be positioned on the beam and will not rotate with respect to each other.

For most purposes the bar or beam 2 is a single piece but for larger work it may be necessary to use an extension arm joint by a coupling 6. The coupling 6 comprises a tubular sleeve, the ends of which are split to form jaws 8. Threaded members 10 at each end of the coupling sleeve 6 when screwed on to the sleeve cam the jaws 8 against the bar or beam to hold it against end-wise movement. One post 12 may be fixed to the beam or may be adjustable along the beam. Its construction basically is similar to that shown in greater detail in connection with adjustable post 14. To this end each of these include a body portion 16 having a suitable opening to receive a needle, pencil or pen holding member 18. As illustrated member 18 is provided with a pin 20. Body portion 16 is drilled to receive the bar or

2

beam 2 and extending upward between the body portion is a threaded stem 22. Slipped over the threaded stem 22 is a collar 24 having a flat bottom surface 26 to bear against the flat top surface 4 of the beam 2. If the beam 2 has other shape than as illustrated, the surface 26 of the collar 24 should be appropriately shaped to bear against the top surface of the bar 2. A spring washer 28 is placed over the threaded portion and above the collar to help hold the post stem 30 in position when the post is released for adjustment. Referring now particularly to post 12 this is fastened in operating position at any convenient place along the bar 2 by slightly unscrewing post stem 30 and sliding the post 12 to its position then screwing post stem 30 to force the collar 24 firmly against the beam 2.

In the case of post 14, its basic structure is as described in connection with post 12 but in addition it may be provided with an extension sleeve 32 integral with body portion 16 and having a coaxial bore. Extension sleeve 32 has an extended counter part in the form of threaded extension sleeve 34 on the opposite side of body portion 16 which similarly has a bore coaxial with the bores of sleeve 32 and body portion 16. In the illustrated embodiment the extension sleeve 34 is externally threaded. A second threaded sleeve 36 is internally threaded to mesh with the external threads of threaded extension sleeve 34. A knurled ring 38 is fastened to the outside of second threaded sleeve 36 to rotate therewith as by a set screw 40 and is provided with an in-turned flange 42 which engages an out-turned flange 44 on a chuck 46. Chuck 46 may comprise two elements such as a split sleeve 48 carrying at one end the out-turned flange 44 and cam member 50 to cam the split portion of sleeve 48 against the beam or bar 2.

40. In operation of the device, the post 12 is set in a predetermined position and the adjustable post 14 is moved along the bar until it is approximately in the correct position. Thereupon the chuck 46 is set on the beam by rotating cam member 50 which tightens the split portion of sleeve 48 against the beam 2. The knurled ring 38 is then rotated in the proper direction to move the post 14 toward or away from the position of the post 12 until the two needle points 50 20 (or other instruments at the end of the posts) are at exactly the desired distance apart as determined from a scale, drawing or other basic data. Thereupon the post stem 30 of post 14 is rotated a slight amount to force collar 24 firmly 55 against the bar 2 to fix the post 14 in the ad-

justed position. It will be noted that the action of fixing the post 14 in its adjusted position cannot in any manner change the relative position of the needle points 20.

It will thus be seen that this invention provides in a beam compass means for adjusting the posts very accurately and in a manner whereby they can be brought to the position of adjustment with great facility and clamped in adjusted position without disturbing the setting. 10

I claim:

A beam compass comprising a solid bar with a flattened top surface, two posts at least one of which is slidable on the solid bar, both posts being held in the same plane by the flattened top surface of the bar, means for locking said slidable post to the solid bar, a first externally threaded sleeve mounted coaxial with said bar and secured to said slidable post, an externally threaded split sleeve slidable over said bar, a knurled nut having an internal tapered surface engaging said externally threaded split sleeve for compressing it to lock said split sleeve to the bar, an internally threaded sleeve engaging

said first externally threaded sleeve and in-turned and out-turned flanges on said internally threaded sleeve and said split sleeve engaging each other around the bar so that when said split sleeve is locked to the bar and said slidable post is unlocked rotation of said internally threaded sleeve will cause an adjustment of said slidable post along the bar.
